BY
Sigmund Herzog ^{ATTORNEY}

Patented Dec. 28, 1926.

UNITED STATES PATENT OFFICE.

ADOLPH LOWY, OF NEW YORK, AND FREDERICK A. HIRSCH, OF MOUNT VERNON,
NEW YORK.

UMBRELLA LOCK.

Application filed October 26, 1925. Serial No. 64,908.

The present invention relates to improvements in umbrellas, and has for its main object to provide a simple, efficient and durable device for preventing the opening of the umbrella by unauthorized persons.

Another object of the invention is to so construct the improvement above referred to that it can be readily applied to umbrellas of any type, without necessitating material changes in the construction of the latter.

A further object of the invention is to so devise the lock that it can be conveniently mounted upon and removed from the umbrella, as the case requires.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawing, which is an elevation, partly in section, of a portion of an umbrella having the locking means mounted thereon.

In the drawings, the numeral 10 indicates an umbrella stick, attached in any suitable manner to a handle 11 of any preferred shape. On the umbrella stick is slidably mounted a runner 12, to which the inner ends of the stretchers 13 of the umbrella frame are pivoted. This runner co-operates in the well known manner with two retainers, one fastening the umbrella in an open position, and the other in closed position. In the drawing a retainer 14 is shown, disposed on the stick 10 a suitable distance from the handle 11, the said retainer being in the form of a spring catch, that is adapted to project through a longitudinal slot 15 in the runner, thereby holding the umbrella in closed position. This spring catch is provided with an aperture 16, through which is adapted to be drawn the shackle 17 of a padlock 18. The

padlock is opened by means of a key, which is inserted thereinto through a keyhole 19. It is, however, obvious that any other lock may be applied, without departing from the invention.

In use, the lock is put in position upon the spring catch, thereby preventing the said catch from being forced into the umbrella stick and, consequently, a disengagement of said catch from the runner. The umbrella is thus prevented from being opened. When the lock is detached from the spring catch, the umbrella operates in the usual, well known manner.

From the foregoing it appears that the only change which is needed in the construction of the umbrella is the provision of the aperture 16 in the spring catch. The device can thus be conveniently manufactured without material increase in the cost thereof. From the foregoing it also appears that an immaterial change in the construction of the umbrella is necessary only to make the improvement herein described, and that this change can be made without in any way affecting the normal operation of the umbrella.

What we claim is:—

1. In an umbrella, the combination with an umbrella stick, of a runner slidably mounted thereon, a spring catch for retaining said runner in position when an umbrella is closed, said spring catch being provided with an aperture, and a lock having an element adapted to be extended through said aperture for preventing disengagement of said spring catch from said runner.

2. In an umbrella, the combination with an umbrella stick, of a runner slidably mounted thereon, a spring catch for retaining said runner in position when the umbrella is closed, said spring catch being provided with an aperture, and a padlock including a shackle adapted to be extended through said aperture for preventing disengagement of said spring catch from said runner.

Signed at New York, in the county of New York, and State of New York, this 6th day of July, A. D. 1925.

ADOLPH LOWY.
FREDERICK A. HIRSCH.
